CONTAINER WITH MECHANISM FOR AGITATING CONTENTS THEREOF

Challies B. Mahan and Hardin B. McDill,
Kansas City, Mo.

Application June 25, 1951, Serial No. 233,322

4 Claims. (Cl. 259—35)

1

The present invention relates in general to containers, and it deals more particularly with a container having means for agitating the contents, as by stirring or beating in the case of liquid contents, or by subjecting the contents to a breaking action if same comprise a granular material which normally is fluent but tends to become caked or encrusted upon standing.

The container of the invention thus is useful, for example, as a storage receptacle for sedimentary liquids or mixtures of immiscible liquids that separate upon standing. Likewise, it finds utility as a receptacle for granular materials such as salt or sugar which sometime become caked in their containers (particularly when exposed to humid atmospheric conditions) and thus must be broken up to restore them to their normal fluent or free-flowing state.

An object of the invention is to provide a container having a built-in agitator and mechanism for actuating same, which agitator and mechanism, however, in no way interfere with the normal use of the container and require no manipulation or handling in connection with the loading and unloading of the container.

Another object is to provide a container having an agitator-actuating mechanism that is concealed at all times during the normal use of the container, yet may readily be inspected for servicing or for any other reason, without disassembly of the mechanism or any part thereof.

A further object is to provide a device of the character indicated whose agitator is actuated by a very simple manual manipulation on the part of the operator, requiring no skill whatever and very little effort. Still another object resides in the provision of a device of the foregoing character which is relatively simple and economical to manufacture, yet is sturdy, long-lived, trouble-free and foolproof in operation.

Other objects, together with the features of novelty whereby the objects are achieved, will in part be obvious and in part pointed out herein-after in the course of the following description of one embodiment of the invention.

In the accompanying drawings which form a part of the instant specification and are to be read in conjunction therewith, and in which like reference numerals are employed to identify like parts in the various views:

Fig. 1 is a sectional elevation of a container for salt or the like, having mechanism for agitating the contents in accordance with the invention.

Fig. 2 is a vertical cross section taken along

the line 2—2 of Fig. 1 in the direction of the arrows,

Fig. 3 is a horizontal cross section taken along the line 3—3 of Fig. 1 in the direction of the arrows, part having been broken away for purposes of illustration, and

Fig. 4 is a horizontal cross section taken along the line 4—4 of Fig. 2 in the direction of the arrows.

Referring more particularly to the drawings, the device there illustrated comprises a vertically elongated, generally cylindrical cup 10, the lower end of which is telescopically received in the upper end of a tubular shell or housing 12. The lower end of the latter is closed by a circular base plate 14 held in place by screws 16, and the plate has an integral centrally located circular boss 18 to which an upstanding cylindrical collar 20 is attached by screws 22.

Collar 20, which hereinafter will sometimes be referred to as the torque collar or tube, thus is co-axial with shell 12, but, as shown, is substantially smaller in diameter than the shell and also shorter, so that its upper end is approximately midway between the ends of the shell. In the collar there are a pair of complementary camming slots 24 and 26 each extending along a helical or spiral path approximately 180° around the axis of the collar so the upper end of one slot is directly above the lower end of the other slot.

Spanning the torque collar diametrically is a horizontal cross bar 28 carrying at its opposite ends a pair of freely turning rollers 30 which are received in the respective ones of said spiral slots. As best seen in Fig. 3, each roller is attached to the cross bar by a screw 32 which extends through the roller and a washer 34 into the end of the bar.

Bar 28 is rigidly attached to a vertical stem or shaft 36 which extends upwardly from the mid-point of the bar, and it is secured thereto by a cap screw 38 whose head is rounded to seat in a hemispherical socket or dimple 40 centrally located in the upper surface of disk 42. A coiled compression spring 44 confined between the disk and the base plate 14 always urges the disk upwardly and thus normally maintains rollers 30 in the upper ends of the respective spiral slots. As indicated in Fig. 2, the upper and lower ends of the spring are seated in shallow retaining and centering wells 46 and 48 in the confronting faces of the disk and base plate respectively.

The central section of the bottom of cup 10 is thickened as shown at 50, and stem 36 extends upwardly therethrough into the cup, being jour-

naled in the bearing hole 52. Below the cup, the stem has an integral enlarged thrust shoulder 54 on which the cup rests, and the portion of the stem within the cup is bifurcated, forming a pair of legs 56 which straddle a paddle or agitator 58. The latter comprises an upright plate containing spaced perforations 60, and it is secured to the stem by rivets 64 extending through aligned holes in the plate and legs 56.

In the embodiment of the invention illustrated, the upper end of cup 10 is reduced in diameter and is externally threaded at 66 to receive a screw cap 68. The cap is perforated as shown at 10 to permit use of the device as a salt shaker or as a dispenser for other granular solids.

So long as the salt or other granular material within the cup 10 is loose and free-flowing, the device is used in conventional fashion, that is to say, by manually lifting it, tilting or inverting it, and shaking to dispense the material through the perforations in cap 68. Of course, when not in use, the unit stands on its flat base in the upright position illustrated. The mechanism is entirely concealed and so far as outward appearance of the device is concerned, shell 12 appears merely to be a slightly enlarged continuation of the wall of cup 10; to the casual observer, in other words, the unit seems simply to be a vertically elongated generally cylindrical container open on the inside all the way from cap 68 down to the bottom plate 64, the side wall of this container being offset outwardly in its lower portion to relieve the severity of its lines. It presents, therefore, a neat and attractive appearance which may be further enhanced, if desired, by appropriate decoration of the exterior of shell 12 and/or cup 10.

If the salt or other granular material within cup 10 becomes caked so that it will not flow freely from the apertures in cap 68, it is only necessary to press downwardly on cap 68 while the device stands in upright position on a table or other supporting surface. The downward thrust is transmitted by the bottom of cup 10 via shoulder 54 to stem 36 which in turn transmits the thrust via the rounded cap nut 38 to disk 42 so that the cup moves downwardly into shell 12 compressing spring 44. Cross bar 28, of course, also moves downwardly with the assembly, whereupon the spiral slots 24 and 26 have a camming effect upon rollers 30 and cause the cross bar, stem 36 and paddle 58 to turn clockwise (Figs. 3 and 4).

The upper end of torque collar 20 serves as a stop against which the bottom of cup 10 abuts to limit the foregoing downward movement of the latter, and when the manually applied downward force is removed, spring 44 obviously will move the cup upwardly, returning it to the position shown. During the return movement the spiral slots 24 and 26 acting on rollers 30 turn cross bar 28, stem 36 and paddle 58 counter-clockwise (Figs. 3 and 4).

By thus reciprocating the cup 10 vertically relative to the housing 12, that is to say, by pushing down on cap 68 one or more times, paddle 58 is caused to turn first in one direction and then in the other, traveling approximately 180° in each direction. This will break up the caked condition of the granular solid in cup 10 so that it may be dispensed through the perforated shaker top 68 in the usual fashion.

The construction of the device illustrated in the drawings and described above, makes it possible to obtain the foregoing advantages as well as others which will be self-evident upon con-

sideration. As previously suggested, the mechanism by which the stirring, agitating or breaking up of the contents of cup 10 is obtained, is entirely concealed from view and the unit as a whole is neat and attractive in exterior appearance so that it is suitable for use in the kitchen, on the dining table or in other places where appearance is a factor of importance.

Further than this, the construction and arrangement of the mechanism is such that it in no way interferes with or complicates the loading of cup 10 with the desired material, or with the dispensing of said material from the cup; for loading purposes, it obviously is necessary only 10 to unscrew cap 68 as one would do if there were no agitating mechanism, and it is unnecessary to remove, displace or handle any part of the mechanism. Hidden from view, this mechanism requires no special consideration of 15 any kind on the part of the operator who ordinarily is scarcely aware of its existence beyond realizing that something always stands ready to rotate the agitator upon pressing down of the cup. The operator therefore is required to have no 20 special knowledge or mechanical ability, for the unit is foolproof, trouble-free and exceedingly simple to use.

At the same time, the mechanism may easily be inspected merely by removing screws 16 and 30 sliding shell 12 up or down relative to the base plate 14. All of the mechanism is assembled on this base plate and the assembly will remain intact even when exposed to view by removal of shell 12. This mode of construction, of course, 35 not only facilitates inspection but also makes the device simple and easy to assemble in the first instance, contributing to the economy of manufacture.

Attention also is directed to the fact that in 40 pressing down on the cup 10 in order to cause rotation of the agitator, advantage is taken of the fact that the operator's hand will resist rotation of the cup with the agitator, yet will yield slightly if the latter encounters more than normal resistance to turning, as when the contents of the cup are caked in unusually hard condition. By utilizing the operator's hand to prevent the cup from turning with the agitator, we eliminate the need for mechanical expedients (such for 45 example, as a vertical spline and groove connection between the exterior of the cup 10 and the interior of shell 12), to prevent turning of the cup. This further simplifies and reduces the cost of manufacture, while at the same time it 50 reduces friction and avoids the binding effect which would exist in a spline connection in the event the agitator encountered more than normal resistance to turning.

The provision of freely rotatable rollers 30 to 55 serve as cam followers in the spiral slots 24 and 26, and the character of the thrust bearing between the cap nut 38 and the disk 42, also materially reduce friction so that the device operates very freely and smoothly.

While the invention has been described in connection with its application to a salt shaker or the like, it will be self-evident that it has many other applications. For example, cup 10 may be used to hold salad oils or dressings made of immiscible liquids that tend to stratify upon standing, in which case vertical reciprocation of the cup will cause the agitator to stir and thoroughly remix the constituents before same are dispensed by pouring; for such use, it is contemplated 70 that the perforated cap 68 would be replaced by

a cap having a suitable pouring spout of conventional design.

Again, the device has wide application to industrial fields, for holding sedimentary liquids which require stirring from time to time in order to get into suspension the solid ingredients which settle out upon prolonged standing. For some uses, it may be desirable to substitute an imperforate cap or closure in place of the perforated cap 68; in other cases, the cap may be omitted entirely, or, as previously suggested, a cap having a pouring spout may be substituted. Likewise, depending upon the use to be made of the device, it may be desirable to depart from the specific construction of the paddle 58 shown in the drawings, and substitute other forms of paddles or agitators well known to those versed in the art.

Inasmuch as various modifications of the invention thus may be made without departing from the scope thereof, it is to be understood that all matter herein set forth or shown in the accompanying drawings is to be interpreted as illustrative and not in a limiting sense.

From the foregoing it will be seen that this invention is one well adapted to attain all of the ends and objects hereinbefore set forth, together with other advantages which are obvious and which are inherent to the structure.

Having thus described our invention, we claim:

1. In a device of the character described, a pair of generally cylindrical cups, the outside diameter of one of said cups conforming to the inside diameter of the other and the closed lower end of said one cup being received in the open upper end of the other cup for telescoping movement of said one cup up and down in said other cup, a vertical shaft journaled in the bottom of said one cup and projecting below same, spring means between the lower end of said shaft and the bottom of said other cup always urging said shaft upwardly, said shaft having an integral annular shoulder abutting the bottom of said one cup for transmitting the thrust of said spring to said one cup, said shaft adapted to move downwardly against the tension of said spring upon downward movement of said one cup relative to said other cup, a torque element fixedly secured in said other cup below the bottom of said one cup and operatively connected to said shaft to rotate same upon axial movement of the shaft, and an agitator in said one cup connected to said shaft to turn therewith.

2. In a device of the character described, a pair of generally cylindrical cups, the outside diameter of one of said cups conforming to the inside diameter of the other and the closed lower end of said one cup being received in the open upper end of said other cup for telescoping movement of said one cup up and down in said

50

60

other cup; a vertical shaft journaled in the bottom of said one cup and adapted to move up and down therewith; camming means in said other cup below the bottom of said one cup for rotating said shaft upon axial movement thereof, said camming means comprising a tubular collar extending upwardly from the bottom of said other cup and containing complementary spiral slots extending helically about the axis of said shaft, and a cross member secured to the lower end of said shaft with the opposite ends of said member received in said slots; an agitator in said one cup connected to said shaft to turn therewith, a horizontal plate within said collar and spaced above the bottom of said other cup; spring means between said plate and the bottom of said other cup always urging the plate upwardly; and a thrust bearing between said plate and the lower end of said shaft for transmitting the upward force of said spring to the shaft.

3. In a device of the character described, a horizontal base having an upstanding collar thereon, said collar containing a pair of complementary spiral slots extending helically about the axis of the collar, a cross member extending diametrically across said collar with its opposite ends received in said slots, spring means between said cross member and said base always urging the cross member upwardly, a cup spaced above said cross member and having vertical side walls, a vertical shaft journaled in the bottom of the cup and secured at its lower end to the mid-point of said cross member, said shaft having an integral annular shoulder below and against the bottom of said cup and supporting same, an agitator in the cup connected to said shaft to turn therewith, and an annular housing extending upwardly from said base and embracing the side walls of said cup, said housing forming a vertical passageway in which said cup is adapted to move up and down relative to said base.

4. A device as in claim 3 having means for releasably securing said housing to said base.
